CLAIM

The ornamental design for a merchandise tag, as shown and described.

DESCRIPTION

FIG. 1 is a front view of a merchandise tag, showing the new design;

FIG. 2 is a front perspective view thereof;

FIG. 3 is a rear view thereof;

FIG. 4 is a rear perspective view thereof;

FIG. 5 is a rear perspective view of the merchandise tag shown in a first alternate position;

FIG. 6 is a front perspective view thereof;

FIG. 7 is a rear perspective view of the merchandise tag shown in a second alternate position;

FIG. 8 is a front perspective view thereof; and,

FIG. 9 is a side view thereof.

The article is shown with a symbolic break in its length. The appearance of any portion of the article between the break lines forms no part of the claimed design.

The uniformly dashed lines shown in the drawings illustrate portions of the merchandise tag which form no part of the claimed design.

The text "360 SURESEAL" forming part of the claimed design is a registered trademark of Secure Authentication Group Corp.
